ENGINE GOVERNOR

Edward M. Claytor, Anderson, Ind., assignor to
General Motors Corporation, Detroit, Mich., a
corporation of Delaware

Application June 1, 1942, Serial No. 445,365

6 Claims. (Cl. 115—34)

This invention relates to engine governors for engines used on motor boats and its object is to prevent the overspeeding of the engine which drives a mosquito boat or other high speed craft which may be used in turbulent waters. A mosquito boat is a light draft boat which skims across the surface of the water. If the water is rough, the propeller is at times out of the water with the result that the engine races while the propeller is unloaded; and, when the propeller, is suddenly submerged, the propeller, transmission and engine are subjected to severe shock. The governor operates to cause the engine to slow down quickly while the propeller is out of the water so that when the propeller strikes the water again it and its driving mechanism will not be subjected to damaging shock.

Further objects and advantages of the present invention will be apparent from the following description, reference being had to the accompanying drawing wherein preferred embodiments of the present invention is clearly shown.

In the drawing:

Fig. 1 is a diagram of a governor embodying the present invention.

Fig. 2 is a diagram of a modified form.

Fig. 1 of the accompanying drawing shows a multi-cylinder internal combustion engine E for driving the propeller P of a boat B steered by a rudder R. Engine E has a fuel intake pipe 21 controlled by a butterfly valve 22 supported by a shaft 23 carrying a lever 24 connected at 25 with a link 26 and with a spring 27 attached to a fixed part 28. Spring 27 tends to rotate the valve 22 in the direction of arrow 22a to close the valve.

The position of the valve 22 is controlled by a servo-motor 30 which, as shown, is an electric motor of the reversible type having fields 31 and 32 wound for excitation of opposite polarity. Motor 31 drives a shaft 33 connected by universal coupling 34 with a shaft 35 rotatable in bearings provided by a bracket 36 and carrying a friction wheel 37 engageable with the arcuate surface 38 of a sector 39 pivoted on a stub shaft 40. Sector 39 is connected by the link 26 with the throttle shaft lever 24. Sector 39 carries two metal segments 41 and 42 connected respectively by wires 41a and 42a with motor fields 31 and 32. A battery or other current source 43 is connected by a wire 44 with a lever 45 pivotally supported by the shaft 40 and having a handle 46. Lever 45 carries a roller 47 engageable with either of the metal segments 41 and 42 or with an insulating segment 48 which separates the

metal segments. Lever 45 carries a pin 49 received by an arcuate slot 50 provided by the sector 39.

Fig. 1 shows roller 47 in contact with the insulating segment 48. Therefore, the motor 30 is disconnected from the battery 43 and the valve 22 is in some position between fully closed and fully opened. Spring 27 is not capable of moving the sector 39 so long as its surface 38 is engaged with the friction wheel 37, since the friction of the motor 30 may be sufficient to resist the spring 27; or the motor 30 might be provided with a brake which is applied when either of the motor fields is disconnected. When it is desired to move the valve 22 further toward open position, which would be effected by counterclockwise rotation of the shaft 23, the lever 46 is moved clockwise to carry the roller 47 into a certain position in contact with the segment 41. This causes motor field 31 to be connected with the battery 43 and the motor turns the wheel 37 in a counterclockwise direction thereby causing sector 39 to move clockwise and to move the valve 22 counterclockwise during further open position. This movement continues until the segment 41 moves away from the roller 47 and the dead spot segment 48 contacts with it. Then rotation of the motor 30 ceases, and the valve 22 remains in the position which has been set by the lever 46. Conversely, when it is desired to move the valve 22 toward closed position, the lever 46 is moved counterclockwise to carry the roller 47 in contact with the motor segment 42, thereby causing motor field 32 to be connected with the battery 43 so that the motor 30 will rotate in a clockwise direction to cause the sector 39 to move counterclockwise to cause the valve shaft 23 to move clockwise in order to move the valve 22 to the closed position. This movement continues until the metal segment 42 leaves the roller 47 and the roller 47 strikes the dead spot segment 48.

The opening and closing of the throttle 22 may be effected manually by moving the lever 46 in either direction through a distance sufficient to cause the pin 49 to engage either end surface of the slot 50. In this way, the sector 39 may be moved manually in either direction by moving the throttle setting lever 46 in case of failure of the servo motor.

The foregoing describes a known form of servo motor operated throttle control used on some types of marine engines. In connection with this type of throttle control, I provide means responsive to movement of the boat such as would cause

propeller to come out of the water for causing the throttle 22 to move almost instantly to closed position. To accomplish this, I provide a water vane switch 60 having a vane 61 adapted to receive the pressure of water as indicated by arrows 62. Vane 61 has an arm 63 carrying a contact 64 for engaging a contact 65 connected by manually operated switch 67 with relay magnet coil 68 and battery 69. A spring 66 urges the contact 64 into engagement with contact 65. Magnet coil 68 is part of a relay 70 having contacts 71 and 72 which connect battery 69 with a solenoid coil 73 for attracting a movable armature 74 toward a stationary core 75. Armature 74 is connected by rod 76 with the bracket 36. A spring 77 compressed between a stationary part 78 and the yoke of the bracket 36 is normally effective to urge the roller 37 into driving engagement with the surface 38 of sector 39.

While the boat is stationary or is moving slowly, switch 67 is kept open so that the governor is non-operative. When the speed of the boat is such that switch 60 is opened by water pressure on vane 61, switch 67 is closed. When due to the bobbing of the boat on rough water, the vane 61 is out of the water, switch 60 closes thereby rendering relay 70 operative to cause contacts 71 and 72 to close in order to connect solenoid coil 73 with the battery 69 and effect the attraction of the armature 74. Wheel 37 is lifted from sector 39 and spring 27 closes the throttle valve 22 to cause the engine to decelerate. Since vane 61 comes out of the water ahead of propeller P, the governor will have started to function ahead of movement of the propeller entirely out of the water. Therefore the engine will begin to decelerate as the propeller comes out of the water.

The water vane 61 is located preferably above the propeller P so that the water vane will come out of the water ahead of the propeller and thus anticipate the needs for deceleration of the engine before the propeller comes out of the water.

Fig. 2 shows a modification in which the means which is responsive to movement of the propeller out of the water controls engine ignition instead of engine throttle. The battery 69 is connected with the engine ignition apparatus designated generally at 80 in Fig. 2 either thru a relay 70a having normally closed contacts 71a and 72a or thru a rotary switch which can be adjusted for continuously passing current to the ignition apparatus or for interrupting flow of current entirely or for providing ignition during a portion of the duration of an engine cycle. This switch comprises a drum 81 mounted on a shaft 82 and driven by a variable speed electric motor 83, the speed of which may be varied in accordance with throttle position if desired. The cylindrical surface of the drum 81 is provided with a metal portion 84 and with a nonconducting portion 85, the slant line 86 denoting the separation of the metal from the insulation. A brush 87 continuously connects the battery 69 with the metal portion 84. The cylindrical surface of the drum 81 is engaged by a brush 88 mounted in a metallic sliding holder 89 which can be moved by handle 90 between metal guides 91 and 92, one of which is connected with the engine ignition. If the handle 90 is moved toward the left, from the position shown, the proportion of the time of one revolution of the drum during which the brush 88 contacts the portion 84 will increase until the proportion is 100% when the brush 88 is in the plane of portion 87. When the brush

88 is moved toward the right the proportion of the time of one revolution of the drum during which the nonconducting portion 85 will be engaged by the brush 88 will increase until that proportion is 100% when the brush 88 is at the right end of the drum. Normally the circuit thru the drum is shorted by the relay contacts 71a, 72a. When the motion of the boat is such as to cause the propeller to come out of the water, the relay coil 68a becomes excited in the manner described with respect to the relay coil 68 in Fig. 1. Then the contacts 71a and 72a will separate and the ignition circuit is then by way of the brush 87, the metal segment 84 and the brush 88. The handles 90 can be set in some predetermined position which will determine just how many sparking impulses of the engine will be eliminated during an engine cycle and thus the speed at which the engine will decelerate when the propeller comes out of the water can be predetermined. By coordinating the handle 90 with the engine throttle lever as indicated in Fig. 2, a predetermined relation between engine speed (determined by throttle position) and rate of engine deceleration (determined by position of handle 90) can be established.

While the embodiments of the present invention as herein disclosed, constitute a preferred form, it is to be understood that other forms 30 might be adopted, all coming within the scope of the claims which follow.

What is claimed is as follows:

1. Apparatus for controlling the speed of the engine which drives the propeller of a motor boat comprising manually controlled means for determining the speed of the engine while the propeller is submerged, means responsive to a motion of the boat which would cause the propeller to come out of the water for temporarily voiding the effect of the manually controlled means and causing the engine speed to be reduced, and including provisions responsive to the forward motion of the boat for withholding the function of voiding the effect of the manually controlled means.

2. Apparatus for controlling the speed of the engine which drives the propeller of a motor boat comprising a throttle for controlling the intake of the engine, a spring for closing the throttle, manually controlled means for determining the throttle opening, and means responsive to a motion of the boat which would cause the propeller to come out of the water for temporarily disconnecting the manually controlled means from the throttle so as to permit the spring to move the throttle toward closed position to cause the engine speed to be reduced.

3. Apparatus for controlling the speed of a multi-cylinder internal combustion engine which drives the propeller of a motor-boat comprising manually controlled means for determining the speed of the engine while the propeller is submerged, ignition apparatus for supplying sparking impulses to the engine, and means rendered operative in response to a motion of the boat which would cause the propeller to come out of the water for temporarily reducing the proportion of the total time of one complete engine cycle during which sparking impulses are provided whereby the engine speed is reduced.

4. Apparatus for controlling the speed of the engine which drives the propeller of a motor boat comprising manually controlled means for determining the speed of the engine while the propeller is submerged, a normally submerged water

vane located above the propeller and attached to the boat and urged by water pressure in a certain direction while it is submerged, a spring for moving the vane the opposite direction when the vane comes out of the water, and means responsive to movement of the vane in the last mentioned direction for temporarily voiding the effect of the manually controlled means and for causing the engine speed to be reduced.

5. Apparatus for controlling the speed of the engine which drives the propeller of a motor boat comprising a throttle for controlling the intake of the engine, a spring for closing the throttle, manually controlled means for determining the throttle opening, a normally submerged water vane located above the propeller and attached to the boat and urged by water pressure in a certain direction while it is submerged, a spring for moving the vane the opposite direction when the vane comes out of the water, and means responsive to movement of the vane in the last mentioned direction for temporarily disconnecting the man-

ually controlled means from the throttle so as to permit the spring to move the throttle toward closed position to cause the engine speed to be reduced.

6. Apparatus for controlling the speed of a multi-cylinder internal combustion engine which drives the propeller of a motor-boat comprising manually controlled means for determining the speed of the engine while the propeller is submerged, ignition apparatus for supplying sparking impulses to the engine, a normally submerged water vane located above the propeller and attached to the boat and urged by water pressure in a certain direction while it is submerged, a spring for moving the vane the opposite direction when the vane comes out of the water, and means responsive to movement of the vane in the last mentioned direction for temporarily reducing the proportion of the total time of one complete engine cycle during which sparking impulses are provided whereby the engine speed is reduced.
